UNITED STATES PATENT OFFICE.

CLARENCE M. HERR, OF CHICAGO, ILLINOIS, ASSIGNOR TO CHARLES T. BLACKFORD AND OSCAR LUDWIG, OF CHICAGO, ILLINOIS.

DISPLAY-BIN FOR COUNTERS, &c.

No. 868,986.

Specification of Letters Patent.

Patented Oct. 22, 1907.

Application filed August 8, 1907. Serial No. 387,619.

To all whom it may concern:

Be it known that I, CLARENCE M. HERR, a citizen of the United States, residing in Chicago, in the county of Cook and State of Illinois, have invented a new and 5 useful Improvement in Display-Bins for Counters, &c., of which the following is a specification.

This invention relates to the construction of the glass bins or compartments now generally used on the tops of show cases, counters and tables in retail stores as a 10 means of displaying the merchandise and keeping it as sorted, according to price, size, or kind.

My object in the invention has been to provide the bins with means whereby they can be partitioned so as to form sub-compartments by the use of glass like that 15 employed in the outside walls of the bins.

The nature of the invention is fully disclosed below, and also in the accompanying drawing forming a part hereof.

In said drawing, Figure 1 is a plan view of the invention. Fig. 2 is a section on line 2—2 of Fig. 1. Fig. 3 is a section on line 3—3 of Fig. 2. Fig. 4 is a view similar to Fig. 2 of a modified construction. Fig. 5 is a section on line 5—5 of Fig. 4.

Referring to the drawing, 6 represents a counter or 25 table upon which my improved compartment display bin has been erected, and 7 represents the glass outside walls thereof, supported by corner posts 8. The posts are provided with feet whereby they may be secured to the counter or table by screws or other proper fastenings. The posts are of metal, and provided with vertical 30 openings or recesses adapted to admit the ends of the glass sections 7.

In order that the bins may be divided into lesser compartments, so as to enable the merchant to keep the 35 different kinds or sizes, or different priced goods in separate divisions, I now provide the bins with posts adapted to support glass partitions 9, the construction of which posts is shown in detail at Figs. 2 and 3. These posts have a body portion 10 upon which may be formed 40 the foot 11 and the bent over top 12. Riveted or soldered to the top are two depending strips 13, 13, each having its top bent at right angles so it may receive the rivet 14 which unites it to the body. These strips may each be provided with feet 15 whereby they may be secured to the counter or table, though this is optional, and they are positioned at such distance apart as to enable the positioning of the partition 9 between them and at right angles to the outside wall. They are also located inside the wall sections 7, and space is left between them and the body of the post for the glass of the 45 outside wall, so that the partition post acts as a brace and support to the same. It will be noted that the

strips 13 are secured to the body in such manner as to permit the use of partitions of the same height as the glass of the outside walls. The strips 13 are shown as 55 made in angle form, but this I do not regard as necessary though it is desirable.

In the modified construction, the post differs from that above described only in the shortening of the strips 13 and the omission therefrom of the feet 15. 60 The post is adapted to be positioned at any point desired upon the outside walls, and the turned over top may be cut out between the strips 13 so that the partition may, if desired, be inserted from above through such cut, this feature being indicated in broken lines at 65 Fig. 1.

I claim:

1. The post for glass display bins, adapted to be secured to the counter or other support, and having an opening for the glass of the outer wall, and depending strips 70 between which a partition arranged at right angles to the outside wall may be positioned.

2. The post for glass display bins, adapted to be secured to the counter or other support, and having a body supporting the outside wall and provided with a turned 75 over top, and strips depending from said turned over top between which a right angle partition may be positioned.

3. The post for glass display bins adapted to be secured to the counter or other support, and having a body adapted to support the glass of the outside wall upon the 80 outer side and having a turned over top, and strips depending from said turned over top and supporting the outside wall upon the inner side, and also having a space between them in which a right angle partition may be positioned.

4. The post for compartment display bins, adapted to be secured to the counter or other support, and to be positioned on the outside wall wherever desired, such post having a vertical space admitting the outside wall, and also having means for holding upright a partition 90 arranged at right angles to the outside wall.

5. The post for compartment display bins, adapted to be secured to the counter or other support, and to be positioned on the outside wall wherever desired, such post having vertical spaces for both the outer wall and a partition 95 extending at right angles to the wall.

6. The post for compartment display bins, adapted to be secured to the counter or other support, and to be positioned on the outside wall wherever desired, such post having vertical spaces admitting the glass of the outer wall and the partition and permitting the glass of both to be of the full height of the post below the turned over top.

7. The post herein described having a body, a turned over top and strips depending from the top and forming 105 with the body vertical spaces for holding upright both the outer wall and the partition.

CLARENCE M. HERR.
